CIGAR MACHINE

Karl Erik Granstedt, Stockholm, Sweden, assignor to Aktiebolaget Formator, Stockholm, Sweden, a corporation of Sweden

Application November 8, 1934, Serial No. 752,142
In Sweden November 10, 1933

6 Claims. (Cl. 131—39)

This invention relates to improvements in cigar machines and more particularly cigar machines of the kind having one or several manually served parts having power members, such as, for instance, a wrapper cutting mechanism or a bunch compressing device.

It is an object of my invention to provide a machine of the kind referred to with a perfectly operating safety device, for preventing accidents which are likely to occur at manually served parts of said machine. Though said safety device is intended to be utilized at different manually served parts of the machine, a wrapper cutting mechanism will be referred to hereinafter as exemplary, since the drawbacks affecting such mechanism are typical to those to be removed by the present invention.

Cutting mechanisms of a common type are provided with a cutting pad and a reciprocating cutting mechanism movable over said pad to cut out a wrapper from a tobacco leaf placed upon the cutting pad. After the cutting operation is finished the cut wrapper is transferred therefrom, whereafter the remaining leaf parts must be removed and another leaf or leaf part is placed upon the cutting pad. The main part of the operations preceding and succeeding the cutting operation proper are executed manually. Thereby risks of accidents will arise. Moreover, the operator being aware of this will hurry when applying the leaf to avoid any touching of the movable cutting members, and hence is not able to take proper care of work so that defective leaves may be placed on the cutting pad or the leaves may be applied in incorrect position. Similar inconveniences will arise also at other manually served parts of the machine, for instance at rotating moulding or compressing drums where the fingers of the operator may by inadvertence be injured.

It is a main object of my invention to remove the drawbacks above referred to.

Another object of my invention is to provide a safety device operating accurately without touching the hands of the operator and even without the operator observing this until the machine has stopped, and thus without troubling the operator in any way.

With these and other objects not specifically mentioned in view, the invention consists in certain constructions, combinations and parts which will be hereinafter fully described and then specifically set forth in the claims hereunto appended.

55 In the drawings, in which similar reference

characters are used to designate corresponding parts throughout the several views, Fig. 1 is a plan view of part of a machine constructed in accordance with the invention; Fig. 2 is an end view of the machine viewed from line II—II of Fig. 1, parts thereof being removed; Fig. 3 is a front view of part of the machine; and Figs. 4 and 5 are different wiring diagrams.

Referring to the drawings, at the front side of the machine frame 1 is provided a cutting pad 3 having a curved cutting knife 2. The cutting pad is perforated and connected to a source of suction, not shown, and, moreover, it is movable up and down to deliver cut-out wrappers to a wrapper carrier, said arrangements being well known in the art and, therefore, further description thereof is in the interest of brevity omitted. A pair of cutting rollers 4 are rotatably mounted on a slide 5 movable along a guide 6 on the machine frame. To the slide 5 is pivotally connected a link 7 which is, in turn, pivoted to a lever arm 8 which is pivotally journaled on a pin 35 fixed to the frame. A roller 11 on the arm 8 runs in a guide groove 12 of a cam disc 9 which is keyed to a shaft 10. The shaft 10 is rotatably journaled in the frame and a cam 24 is fixed to said shaft. A pair of intermeshing bevel gears 34 are arranged at the inner end of the shaft 10 and one of said gears is integrally formed with the cam 24. On the inner extremity of the shaft 10 is mounted a clutch member 13 which is axially displaceable but not rotatable relative to said shaft. Between said clutch member and a ring 36 secured to shaft 10 is interposed a coiled spring 53 which urges the clutch member 13 against another clutch member 15 keyed to a continuously rotating driving shaft 14, coaxial with shaft 10. The bevel gears 34 drive a shaft 37 which is adapted to drive several operating mechanisms of the machine, e. g. the wrapper carrier 26 and a wrapping mechanism to which said carrier transfers cut-out wrappers from the cutting pad 3. The wrapper carrier 26 is pivotally mounted in the machine frame and provided with an arm 60 which is actuated by a cam 61 mounted on the shaft 37 so as to swing the wrapper carrier between the cutting pad 3 and a cigar wrapping mechanism (not shown).

To actuate the clutch, a bell crank lever is pivoted on a pin 16 in the frame. One arm 38 of said lever carries a roller 39 which runs in an annular groove 40 of the clutch member 13 and the other arm 17 of the lever is pivoted to a link 18. The link 18 is pivotally connected to a lever

arm 19. The lever arm 19 is pivoted on a pin 20 in the machine frame and its free end is integrally formed with a weight 21. A magnet core 22 is slidably and pivotally connected to the arm 19 and enclosed by an electro-magnet 23.

Upon the cam 24 rests under the influence of a spring 41 a rod 25 slidably mounted in the frame below the weight 21. The shape of the curved portion of the cam 24 and the angular position of said cam relative to the cam disc 9 are such that the rod is against the pressing action of the spring 41 held in its uppermost position (Fig. 2) during the part of the cycle of operation of the machine that follows upon the cutting-out of a wrapper until the cutting rollers 4 are to be advanced over the cutting pad 3.

In the proximity of the cutting pad 3 is mounted an incandescent lamp 27 and opposite to the lamp is mounted a photo-cell 28 so that rays of light emanating from the lamp will fall upon the light sensitive surface of the photo-cell.

It is provided that the photo-cell indicated in the diagram shown in Fig. 4 consist of the well known type, the resistance of which to electric currents increases according to the decreasing of the amount of light falling upon its light sensitive surface. The incandescent lamp and the photo-cell are connected to circuits, each of which is connected to a common main circuit. The circuit of the photo-cell includes a series resistance 29 and a relay 30 arranged to alternately close and break a main circuit to which is connected the electro-magnet 23.

The photo-cell indicated in Fig. 5 is of the well known type which generates a feeble current in a circuit when its light sensitive surface is illuminated. To said circuit, termed the primary circuit, is connected a sensitive relay 31 of well known structure which when its coil is energized will close a secondary circuit connected to the main circuit and including a series resistance 32 and a relay 33 which is arranged to alternately break and close the main circuit. The electro-magnet 23 is connected to said main circuit. It is in this case provided by way of example that the rays of light are transmitted from the lamp to the photo-cell by the intermediary of reflectors 51 and 52. Thereby it is possible to arrange the lamp and the photo-cell practically anywhere in the machine.

When using the wiring according to Fig. 4 the embodiment of the invention now described operates in the following manner:

When the cutting mechanism occupies its initial position shown in Figs. 1 and 3 the lamp 27 illuminates the photo-cell 28, the resistance of which is, therefore, so slight that the current of the circuit can influence the relay 30 to close the main circuit, thereby causing the electro-magnet 23 to attract the core 22 which will couple the clutch 13, 15. Then the cam 24 holds the rod 25 in its raised position. When the operator places a tobacco leaf on the cutting pad 3 her hands will interrupt the optical communication between the lamp 27 and the photo-cell 28 and then the resistance of the latter will increase so that the intensity of current in the primary circuit is decreased to such a degree that the relay will break the main circuit and the coil of the electro-magnet is demagnetized. Then the magnet core 22 cannot support the rod 19, but nevertheless the rod cannot fall down as the weight 21 rests on the rod 25. When the cycle of operation has proceeded so far that the cutting mechanism is about to advance the cam 24 will permit

the spring 41 to move the rod 25 downwards. In case the operator should not then have withdrawn her hands the weight 21 forces the arm 19 and link 18 downwards, the bell crank lever will release the coupling 13, 15, the cutting mechanism is not advanced and the mechanisms driven by the shaft 37 are arrested. If, however, the operator retracts her hands before the beginning of the critical period now mentioned the electro-magnet will immediately be magnetized and it is able to retain the arm 19 in its upper position, i. e. the clutch 13, 15 remains coupled irrespective of the fact that the rod 25 does not support the weight 21. This is effected thereby that the optical communication between the lamp 27 and the photo-cell 28 is restored in due time, the resistance of the photo-cell is considerably decreased, and the primary current influences the relay 30 to close the main circuit. Should, however, the operator by inadvertence hold her hands so close by the cutting mechanism already in operation that her hands might be injured the optical communication will instantly be interrupted and the clutch 13, 15 released. After the cutting operation has been finished, there will no longer be any risk of accidents. Then the rod 25 is automatically forced upwards by the cam to support the weight 21 and consequently the cutting-out of the main circuit which will necessarily occur at the next tobacco leaf applying will not cause the clutch to be released and thus the other mechanism of the machine will still operate. The locking effect of the rod 25 is maintained until the cycle of operation is finished and the critical period above mentioned is to commence anew.

The abutting mechanism actuating the arm 19 may possibly be replaced by a mechanism directly actuating a circuit, for instance the main circuit as indicated in Fig. 4, according to which the cam 24 is adapted to periodically move the rod 25 to positively cause the relay 30 to close the main circuit. Said closing takes place at the same periods of the operating cycle as if the rod 25 had to actuate the weight 21.

When using the wiring diagram according to Fig. 5, the cutting mechanism, the clutch, the mechanical locking or abutting device, and the electro-magnet operate exactly in the same manner as previously described, whereas the operations of the circuits are somewhat different. The main circuit is maintained closed by the relay 33 when the secondary circuit is maintained closed, which is the case when the sensitive relay 31 is actuated by the current-carrying primary circuit. Said primary circuit is current-carrying when the lamp 27 illuminates the photo-cell 28, which when affected by rays of light generates a feeble current.

Though I have now described embodiments of the invention relating to a wrapper cutting device, it should be observed that my invention is also applicable to other manually operated parts of the machine, such as, for instance, bunch compressors. Such bunch compressors are, for instance, described in my United States Patent No. 1,982,292, dated November 27, 1934. The bunch compressing drum 42, shown in Fig. 1, has a plurality of peripheral pockets 43 into which the bunches are inserted manually by the operator. The drum 42 is fixed to the shaft 63 which is rotatably journalled in the machine frame and carries an eccentric 54 embraced by a strap 44 which latter is connected to a rod 45 pivoted to the arm 46. Stepwise rotary movement is im-

parted to the drum 42 by a Geneva wheel 64, for secured to the shaft 63, driven by the shaft 10. The arm 46 is pivotally connected to the machine frame 1 and is loosely fitted within an opening 47 in a sliding rod 48. The rod 48 is reciprocally movable in a guide 49 in the frame and formed integrally with a die 50 which is recessed in accordance with the shape of the bunches to be compressed. The incandescent lamp 27 and the photo-cell 28 are arranged to emanate and receive, respectively, rays of light passing over the die 50 in the proximity of the drum 42. The shape and angular position of the eccentric 43 on the shaft 10 are such relative to the cam (Fig. 2) that if the optical communication between the lamp and the photo-cell is interrupted when the die 50 is about to advance into a pocket 43 the rod 25 (Fig. 2) will permit the arm 19 to fall down and the machine is stopped. Consequently, if the hands of the operator are in the proximity of the die when the latter is about to advance there is no risk that her hands will get crushed.

Of course, the rays of light transmitted from the lamp to the photo-cell may be invisible.

I claim:

1. In a cigar machine, a die, a mechanism having a tool adapted to coact with said die, another mechanism having a tool, a joint means for driving said mechanisms in timed relationship to perform repeated successive operations in which the die tool moves to and from said die, means for arresting said joint driving means, control means including a light-sensitive device and a source of light for controlling said arresting means according to whether the light sensitive device is shielded from the source of light by a human hand in the proximity of said die, and automatic means including a latch member operative in timed relation to said joint driving means to hold said arresting means out of operation while the tool that coacts with said die is sufficiently removed from said die to allow safe manual access to said die so that the cycle of operations of the machine continues while the light sensitive means is shielded until the die tool is about to approach dangerously close to the die.
  2. In a cigar machine, a wrapper cutting die, a wrapper cutter, a mechanism for moving said wrapper cutter across said wrapper cutting die, a leaf carrier, mechanism for moving said leaf carrier into and out of position above said wrapper cutting die, a joint means for driving said mechanisms in timed relationship to perform repeated successive operations, in which the cutter moves to and from the die, means for arresting said joint driving means, control means including a light sensitive device and a source of light for controlling said arresting means according to whether said light sensitive means is shielded from said source of light by a human hand in the proximity of said wrapper cutting die, and automatic means including a latch member operative in timed relation to said joint driving means to hold said arresting means out of operation when the wrapper cutter is sufficiently removed from the cutting die to allow safe manual access to said die so that the cycle of operations of the machine continues while the light sensitive means is shielded until the die tool is about to approach dangerously close to the die.
  3. In a cigar machine, a bunch compressing device having a die, a bunch compressing tool, a mechanism for moving said tool into said die, another mechanism having a tool, a joint means
- for driving said mechanisms in timed relationship to perform repeated successive operations, in which the bunch compressing tool moves to and from the die, means for arresting said driving means, control means including a light-sensitive device and a source of light for controlling said arresting means according to whether the light sensitive means is shielded from said source of light by a human hand in the proximity of said die, and automatic means including a latch member operative in timed relation to said joint driving means to hold said arresting means out of operation when the said compressing tool is sufficiently removed from said die to allow safe manual access to said die so that the cycle of operations of the machine continues while the light sensitive means is shielded until the die tool is about to approach dangerously close to the die.
4. In a cigar machine, a die, a mechanism having a tool which is adapted to coact with said die, another mechanism having a tool, a joint means for driving said mechanisms in timed relationship to perform repeated successive operations, said driving means including, a clutch, clutch releasing means, control means including a light sensitive device and a source of light for controlling said clutch releasing means according to whether the light sensitive means is shielded from said source of light by a human hand in the proximity of said die, a latch member, and automatic means operative in timed relation to said joint driving means for intermittently moving said latch member to hold said clutch releasing means out of operation when the tool that cooperates with said die is sufficiently removed from said die to allow safe manual access to said die so that the cycle of operations of the machine continues while the light sensitive means is shielded until the die tool is about to approach dangerously close to the die.
5. In a cigar machine, a die, a mechanism having a tool adapted to coact with said die, another mechanism having a tool, a joint means for driving said mechanisms in timed relationship to perform repeated successive operations in which the die tool moves to and from said die, said driving means including a clutch, an electric circuit, electromagnetic means connected in said circuit for controlling said clutch, means, including a light sensitive device and a source of light, for controlling the said electromagnetic means according to whether the light sensitive means is shielded from said source of light by a human hand in the proximity of said die, and automatic means including a latch member operative in timed relation to said joint driving means for intermittently holding said control means out of operation when the tool that coacts with said die is sufficiently removed from said die to allow safe manual access to said die so that the cycle of operations of the machine continues while the light sensitive means is shielded until the die tool is about to approach dangerously close to the die.
6. In a cigar machine, a die, a mechanism having a tool adapted to coact with said die, another mechanism having a tool, a joint means for driving said mechanisms in timed relationship to perform repeated successive operations in which the die tool moves to and from the die, said driving means including a clutch, clutch operating means, an electric circuit, electromagnetic means connected in said circuit for controlling said clutch operating means, a switch in said circuit for controlling said electromag-

netic means, means, including a light sensitive device and a source of light, for controlling said switch to control said electromagnetic means to control said clutch operating means when the light sensitive means is shielded from said source of light by a human hand in the proximity of said die, a latch member, and automatic means operative in timed relation to said joint driving means for intermittently moving said latch mem-

ber to hold said control means out of operation when the tool that coacts with said die is sufficiently removed from said die to allow safe manip. access to said die so that the cycle of operations of the machine continues while the light sensitive means is shielded until the die tool is about to approach dangerously close to the die.

KARL ERIK GRANSTEDT.
